ULTRAHIGH FREQUENCY ELECTRON TUBE

Jack A. McCullough, Millbrae, Calif., assignor to
Eitel-McCullough, Inc., San Bruno, Calif., a
corporation of California

Application May 31, 1950, Serial No. 165,256

13 Claims. (Cl. 313—257)

1

My invention relates to improvements in electron tubes of the negative grid type in which electron transit time effects necessitate small clearances between the electrodes for satisfactory operation at the ultra-high frequencies. The invention also relates to improvements particularly well suited for incorporation in a tube of annular construction such as disclosed in the copending application, Serial No. 86,232 filed April 8, 1949. In such an annular tube having planar electrodes it is possible to provide ample electrode areas for larger power outputs, thus laying the foundation for high power tubes in the ultra-high frequency range.

An object of my invention is to provide a tube structure having improved means for precisely establishing the close spacings required between the electrodes, particularly the critical spacing between the grid and cathode.

Another object is to provide means which accurately maintains the desired close electrode spacings independently of relative expansions occurring in the tube envelope.

Another object is to provide electrode spacing means of the character described which is suitable of incorporation in a tube of annular construction.

Still another object includes the provision of further improvements in the annular type of tube, whereby the fabrication and assembly of the annular envelope and ring-shaped electrodes is facilitated.

The invention possesses other objects and features of advantage, some of which, with the foregoing, will be set forth in the following description of my invention. It is to be understood that I do not limit myself to this disclosure of species of my invention as I may adopt variant embodiments thereof within the scope of the claims.

Referring to the drawings:

Figure 1 is a vertical sectional view of a triode type of annular tube embodying the improvements of my invention; and

Figure 2 is a bottom view of the same.

Figure 3 is a view similar to Figure 1, showing only half the tube, illustrating a modified internal construction.

Figure 4 is a vertical sectional view of another tube embodying my improvements, illustrating a tetrode rather than a triode and also showing a modified envelope construction.

In terms of broad inclusion my improved electron tube comprises an envelope, electrodes, a spacer of insulating material in the envelope and interposed between the electrodes for establish-

ing the electrode spacing, and spring means pressing the electrodes together against the spacer. In my preferred annular tube construction the envelope comprises concentric inner and outer side walls, the electrodes being ring-shaped and supported between the walls, and the electrode spacers being rings concentric with the side walls. In an annular triode, for example, a pair of concentric spacer rings is provided between the grid and cathode and another pair of spacer rings is preferably provided between the grid and anode. The ring-shaped grid is preferably floatably mounted between the side walls, and spring means is preferably interposed between the grid and envelope for pressing the grid toward the cathode. In this improved annular tube construction the side walls of the envelope preferably contain pairs of metallic terminal rings with which flanges on the electrode assemblies are engaged, the electrode assemblies being designed for insertion between the side walls after the parts have been separately fabricated. The cathode and anode assemblies are connected to the end pairs of terminal rings by fused metallic bonds, and the grid assembly is preferably floatably mounted by frictional contact with an intermediate pair of terminal rings. In putting the triode together the cathode assembly is first fixed to the side walls at the lower end of the envelope, the grid assembly is then inserted together with the associated spacer rings, and then the anode assembly and additional spacers (including the spring loading means) are inserted over the grid assembly, after which the anode assembly is fixed to the side walls at the upper end of the envelope, thus locking all of the parts together. If a tube having more than one grid such as a tetrode is being constructed in accordance with my invention, additional spacers are provided between the several grid assemblies.

In greater detail, and referring first to the triode shown in Figures 1 and 2, my improved ultra-high frequency electron tube structure as incorporated in an annular type of tube comprises an envelope having concentric inner and outer side walls providing an annular evacuated closure for a plurality of ring-shaped electrodes including anode 2, cathode 3, and control grid 4. The electrodes are preferably of the planar kind in which the opposed active surfaces of the electrodes lie in parallel planes transverse to the tube axis. In a tube of this kind the electrode dimensional limit on frequency is the width and not the circumferential length of the electrodes. For an ultra-high frequency tube the effective electrode width measured across the section of

the ring-shaped electrodes would be quite small, say about $\frac{3}{8}$ inch for frequencies of the order of 2000 megacycles. The diameter of the tube may be of any desirable size, however, depending upon the active electrode required for the power output desired. With this annular type of tube structure it is thus possible to design high power tubes in the ultra-high frequency range.

The side walls of the envelope have insulator sections 6 of a suitable insulating material such as glass or ceramic sealed between suitable metallic rings, which rings are aligned in pairs to provide a pair of cathode terminal rings 7 at the lower ends of the walls, a pair of anode terminal rings 8 at the upper ends of the walls, and a pair of grid terminal rings 9 intermediate the ends. The several rings have offsets so that the side walls diverge toward the upper portion of the envelope for insertion of the electrode assemblies as hereinafter described.

In the envelope construction shown in Figure 1, the terminal rings are formed of sheet metal and glass sections 6 are sealed to the edges of the rings with lapped seals, which is a conventional type of glass-to-metal seal. An important feature of my tube construction is that the inner and outer side walls may be separately fabricated as simple cylinders prior to assembling the envelope, so that the various glass-to-metal seals incorporated in the side walls may be readily made in an ordinary glass lathe.

After the side walls have been completely fabricated the inner wall is inserted within the outer wall, whereupon these parts are ready for further assembly of the envelope. The several ring-shaped electrode assemblies, including anode 2, cathode 3 and grid 4, are also separately fabricated as complete units and are so designed that they may be inserted between the side walls, which provides a simple and effective procedure for making the tube.

Cathode 3 may embody any conventional type of electron emitter material, such as thoriated tungsten or a coating of barium and strontium oxides, the oxide type of cathode being well suited for my tube construction and therefore preferred. The ring-shaped cathode is conveniently formed as a circular channel stamped from a metal such as nickel, which channel presents a flat face for receiving the oxide coating to provide the active surface of the cathode facing the grid. The cathode is supported by a ring-shaped header 16, also formed as a circular channel stamped from suitable sheet metal, having a center rib 11 to which the cathode piece is connected, and also having outwardly and downwardly extending supporting flanges 16. The cathode assembly includes a heater which preferably comprises a flat spiral coil 12 embedded in a suitable insulating material 13 located in the channel-shaped cathode. One end of the heater wire is connected to the cathode mount and the other end is brought out by a lead 14 sealed through the header.

The completed cathode assembly is inserted between the side walls so that downwardly extending flanges 16 of the header register with the lower pair of terminal rings 7. This cathode assembly which forms the bottom wall of the envelope is then fixed in position by fused metallic bonds, as by brazes 17 along the registering edges of flanges 16 and end rings 7.

The flat ring-shaped grid is fabricated in any suitable manner, as by wires stretched across a pair of retaining rings 18. The grid is supported

along both of its peripheral edges by circular metal flanges 19 having upturned lips or fingers engaging the intermediate pair of terminal rings 9. This grid assembly is insertable between the walls from the top of the envelope. The grid-to-cathode spacing is established by a pair of concentric spacer rings 21 of suitable insulating material such as glass or ceramic, a material having a low coefficient of thermal expansion such as quartz, being preferred. These spacer rings are interposed between the grid and cathode, preferably between the supporting flanges 19 and 16 which flanges are shaped with circular flats or ledges to provide seats for holding the spacer rings concentric. The spacers 21 are placed in position and then the grid assembly is inserted and lowered down against the spacers.

Such arrangement not only facilitates assembly of the tube but also provides an excellent means for establishing very close and accurate spacings between the electrodes. For example, the parts may be very accurately dimensioned, as by precision grinding the spacer rings to size, to set the electrode spacing within a fraction of a thousandth of an inch. Such precision is especially important in ultra-high frequency tubes where the electrode spacings are very small, particularly at the grid-to-cathode spacing which is most critical in tubes of this kind.

After the grid assembly has been brought down firmly against the spacers 21 the grid flanges 19 may be fixed to terminal rings 9 as by spot welding. I prefer, however, to maintain connection between these parts by frictional contact for reasons later discussed.

Ring-shaped anode 2 is preferably of the external anode type machined of a suitable metal such as copper for good heat conduction. Its inner portion terminates at a flat face providing the active surface of the anode facing the grid, and its outwardly projecting portion is accessible for application of a suitable cooler (not shown) which may be a finned radiator for air cooling or a jacket for water cooling. The anode assembly includes a pair of diverging metallic flanges 22 fastened to the lower portions of the anode, which flanges register with the upper pair of terminal rings 8. This anode assembly also preferably includes the exhaust tubulation 23 communicating with the interior of the envelope through passage 24, the tubulation being pinched off at tip 26 after evacuation of the envelope.

The completed anode assembly is mounted by insertion between the side walls and forms the top wall of the envelope. The grid-to-anode spacing, while usually wider and not as critical as compared to the grid-to-cathode spacing, is nevertheless preferably established by a second pair of internal concentric spacer rings 27 of insulating material. These spacers are interposed between the grid and anode and are held concentric by suitable flats or seats provided in the supporting flanges of these electrodes, the spacers 27 being preferably vertically aligned with grid-cathode spacer rings 21.

Spacers 27 are inserted after the grid assembly and then the anode assembly is lowered down against the spacers. When firmly seated the anode assembly is fixed by fused metallic bonds such as brazes 28 along the registering edges of flanges 22 and end rings 8. The grid assembly is thus positively locked in place between the anode and cathode without requiring fixed connections at grid terminal rings 9. All of the electrode spacings are thus established and

maintained by the internal spacer rings 21 and 27, the grid being mechanically floating between the other two electrodes and held precisely spaced therefrom by the precision cut spacers.

The internal structure is preferably spring loaded to maintain a constant pressure on the grid structure toward the cathode. In the construction of Figure 1, a certain degree of spring loading is provided by the flexibility in the metal top wall flanges 22 when the latter are pressed down in final position against the spacers 21. Another means for accomplishing this is shown in Figure 3 comprising small coil springs disposed in recesses along the upper edges of spacer rings 21 and bearing against the flanges 22. In either case the spring means thus interposed between the envelope and floating grid assembly serves to force the grid and cathode assemblies together against the interposed spacers 21. The grid is thus always pressed toward the cathode to insure maintenance of the critical grid-to-cathode spacing even though differential expansions may occur in other parts of the tube. As already pointed out, the grid-to-cathode spacing is less critical so that any slight variations which might occur due to envelope expansion can be taken up in the cathode-to-anode region by the springs 29 without serious problem in the operation of the tube.

Figure 4 shows the tetrode version of my tube to illustrate the inclusion of more than one grid. In this case a screen grid 31 is positioned between the control grid 4 and anode 2, and an additional pair of concentric spacer rings 32 are interposed between the grids for establishing the control grid-to-screen grid spacing. Figure 4 also illustrates a modified and more compact side wall construction embodying butt-type glass or ceramic-to-metal seals. The fact that the side walls may be fabricated separately makes this seal construction possible in an annular tube. Here the various terminal rings, including the cathode terminals 33, control grid terminals 34, screen grid terminals 36, and anode terminals 37 are all formed with disk-like sealing surfaces against which the insulator ring sections 38 are sealed in abutting relation.

In the tetrode construction the supporting flanges of both the control grid and screen grid preferably have frictional contact with the terminal rings so that both the grid structures are mechanically floating and subject to precisely held spacings with respect to the cathode. As in the case of the triode additional spring loading on the grids may be provided by separate springs similar to those shown in Figure 3. The critical grid-to-grid and grid-to-cathode spacings are thus positively established and maintained by the spacers 21 and 32, which spacings are maintained independently of relative expansions that might take place in the envelope structure.

While many of the improvements described are particularly applicable to the annular type of tube it is understood that certain features such as the structure for establishing and maintaining close electrode spacings may be incorporated in other types of tubes such as tubes of the conventional cylindrical or tubular shape.

I claim:

1. An electron tube comprising an envelope having a circular side wall, a metallic terminal ring on the side wall, an electrode fixed adjacent an end of the envelope, an electrode extending transversely of the envelope axis and slidably

engaging the terminal ring, and a spacer ring of insulating material within the envelope between the electrodes to establish the spacing of the slideable electrode from said fixed electrode.

5. An electron tube comprising an annular envelope having concentric inner and outer side walls, metallic terminal rings on the side walls, a ring-shaped electrode fixed adjacent an end of the envelope, a ring-shaped electrode extending transversely of the envelope axis and slidably engaging the terminal rings, and spacer rings of insulating material within the envelope between the electrodes to establish the spacing of the slideable electrode from said fixed electrode.

10. An electron tube comprising an annular envelope having concentric inner and outer side walls, ring-shaped electrodes having opposed active surfaces supported between the side walls, spacer rings of insulating material within the envelope and interposed between the electrodes, and a spring means pressing the electrodes together against said spacer rings.

15. An electron tube comprising an annular envelope having concentric inner and outer side walls, ring-shaped electrodes having opposed active surfaces supported between the side walls, spacer rings of insulating material within the envelope and interposed between the electrodes, and a spring means pressing the electrodes together against said spacer rings.

20. An electron tube comprising an annular envelope having concentric inner and outer side walls, ring-shaped electrodes having opposed active surfaces including a cathode and grid and anode, pairs of metallic terminal rings on said side walls, metallic supporting flanges on the cathode connected to a pair of said terminal rings, metallic supporting flanges on the grid connected to a second pair of said terminal rings, metallic supporting flanges on the anode connected to a third pair of said terminal rings, a pair of concentric spacer rings of insulating material within the envelope between said flanges of the grid and cathode, and a second pair of concentric spacer rings of insulating material within the envelope between said flanges of the grid and anode.

25. An electron tube comprising an annular envelope having concentric inner and outer side walls, ring-shaped electrodes having opposed active surfaces including a cathode and grid and anode, pairs of metallic terminal rings on said side walls, metallic supporting flanges on the cathode connected to a pair of said terminal rings, metallic supporting flanges on the grid connected to a second pair of said terminal rings, metallic supporting flanges on the anode connected to a third pair of said terminal rings, a pair of concentric spacer rings of insulating material within the envelope between said flanges of the grid and cathode, the connections between the grid supporting flanges and said second pair of terminal rings being frictional contacts, and spring means pressing the grid toward the cathode.

30. An electron tube comprising an annular envelope having concentric inner and outer side walls, ring-shaped electrodes having opposed active surfaces including a cathode and grid and anode, pairs of metallic terminal rings on the ends of said walls, metallic supporting flanges on the cathode registering with the terminal rings at one end of the envelope, metallic supporting flanges on the anode registering with the terminal rings at the other end of the envelope, and fused metallic bonds uniting said flanges with the respective terminal rings.

35. An electron tube comprising an annular envelope having concentric inner and outer side walls, ring-shaped electrodes having opposed active surfaces including a cathode and grid and anode, pairs of metallic terminal rings on the ends of said walls, metallic supporting flanges on the

cathode registering with the terminal rings at one end of the envelope, metallic supporting flanges on the anode registering with the terminal rings at the other end of the envelope, fused metallic bonds uniting said flanges with the respective terminal rings, another pair of terminal rings on said walls intermediate the ends thereof, and metallic supporting flanges on the grid connected to said last mentioned pair of terminal rings.

8. An electron tube comprising an annular envelope having concentric inner and outer side walls, ring-shaped electrodes having opposed active surfaces including a cathode and grid and anode, pairs of metallic terminal rings on the ends of said walls, metallic supporting flanges on the cathode registering with the terminal rings at one end of the envelope, metallic supporting flanges on the anode registering with the terminal rings at the other end of the envelope, fused metallic bonds uniting said flanges with the respective terminal rings, another pair of terminal rings on said walls intermediate the ends thereof, metallic supporting flanges on the grid connected to said last mentioned pair of terminal rings, and spacer rings of insulating material within the envelope and interposed between the electrodes.

9. An electron tube comprising an envelope having concentric inner and outer side walls, pairs of metallic terminal rings on the upper and lower ends of said walls, another pair of metallic terminal rings on said walls intermediate the ends thereof; a ring-shaped cathode electrode assembly insertable between said walls and having metallic supporting flanges connected to the lower pair of terminal rings; a ring-shaped grid electrode assembly insertable between said walls and having metallic supporting flanges connected to the intermediate pair of terminal rings; and a ring-shaped anode electrode assembly insertable between said walls and having metallic supporting flanges connected to the upper pair of terminal rings.

10. An electron tube comprising an envelope having concentric inner and outer side walls, pairs of metallic terminal rings on the upper and lower ends of said walls, another pair of metallic terminal rings on said walls intermediate the ends thereof; a ring-shaped cathode electrode assembly insertable between said walls and having metallic supporting flanges connected to the lower pair of terminal rings; a ring-shaped grid electrode assembly insertable between said walls and having metallic supporting flanges connected to the intermediate pair of terminal rings; a ring-shaped anode electrode assembly insertable between said walls and having metallic supporting flanges connected to the upper pair of terminal rings; and concentric spacer rings of insulating material interposed between the grid and cathode assemblies.

11. An electron tube comprising an envelope having concentric inner and outer side walls, pairs of metallic terminal rings on the upper and lower ends of said walls, another pair of metallic terminal rings on said walls intermediate the ends thereof; a ring-shaped cathode electrode assembly insertable between said walls and having metallic supporting flanges connected to the lower pair of terminal rings; a ring-shaped grid electrode assembly insertable between said walls and

having metallic supporting flanges connected to the intermediate pair of terminal rings; a ring-shaped anode electrode assembly insertable between said walls and having metallic supporting flanges connected to the upper pair of terminal rings; and concentric spacer rings of insulating material interposed between the grid and cathode assemblies; the connections between the flanges of the grid assembly and said intermediate pair of terminal rings being frictional contacts.

12. An electron tube comprising an envelope having concentric inner and outer side walls, pairs of metallic terminal rings on the upper and lower ends of said walls, another pair of metallic terminal rings on said walls intermediate the ends thereof; a ring-shaped cathode electrode assembly insertable between said walls and having metallic supporting flanges connected to the lower pair of terminal rings; a ring-shaped grid electrode assembly insertable between said walls and having metallic supporting flanges connected to the intermediate pair of terminal rings; a ring-shaped anode electrode assembly insertable between said walls and having metallic supporting flanges connected to the upper pair of terminal rings; concentric spacer rings of insulating material interposed between the grid and cathode assemblies; the connections between the flanges of the grid assembly and said intermediate pair of terminal rings being frictional contacts.

13. An electron tube comprising an envelope having concentric inner and outer side walls, pairs of metallic terminal rings on the upper and lower ends of said walls, another pair of metallic terminal rings on said walls intermediate the ends thereof; a ring-shaped cathode electrode assembly insertable between said walls and having metallic supporting flanges connected to the lower pair of terminal rings; a ring-shaped grid electrode assembly insertable between said walls and having metallic supporting flanges connected to the intermediate pair of terminal rings; a ring-shaped anode electrode assembly insertable between said walls and having metallic supporting flanges connected to the upper pair of terminal rings; concentric spacer rings of insulating material interposed between the grid and cathode assemblies; the connections between the flanges of the grid assembly and said intermediate pair of terminal rings being frictional contacts, and the connections between the flanges of the cathode and anode assemblies and said end pairs of terminal rings being fused metallic bonds.
